DETACHABLE BRIDGE SPRING CONNECTION

Application filed December 20, 1929. Serial No. 415,492.

This invention relates to ophthalmic mountings, and has particular reference to an improvement in a detachable connection between a bridge spring and a socketed terminal element which attaches the bridge

5 spring of a folding Oxford to the lens frame. In that form of detachable connection illustrated, where the terminals of the bridge spring are snugly fitted into the terminal element and said terminal element is provided with a slot to receive a spring tongue designed to snap into the socket when the terminal of the bridge spring is shoved home in the socket, difficulties have arisen where the spring 10 tongue fails to spring into place for locking the spring in connected relation with the terminal element. This difficulty may arise where the nature of the material from which the bridge spring is constructed fails to im-

15 part to the small tongue the necessary resiliency or where, for other reasons, the locking tongue fails to move to its locking position. The present invention, therefore, comprehends broadly a means for facilitating the 20 positive deflection of the tongue into the slotted portion of the terminal element, which means specifically consists in providing the terminal element with an apertured portion communicating with the socket and disposed 25 opposite the slotted tongue receiving portion of the terminal element for permitting of the introduction through said aperture of an im-

30 plement to positively deflect the tongue from the plane of the bridge spring to a position 35 where it engages with the wall of the slotted portion.

The present invention further aims to provide in a bridge spring terminal element of the character set forth, a means for facilitating the positive deflection of the locking tongue into locking engagement, which means is extremely simple, does not materially add to the expense of production and which is highly efficient in its purpose.

40 With the above recited and other objects in view, reference is had to the following description and accompanying drawings, in which there is exhibited one example or embodiment of the invention, while the claims 45 define the actual scope of the same.

In the drawings:

Figure 1 is a fragmentary front view of a folding Oxford frame illustrating the detachable bridge spring associated with the terminal element.

55 Figure 2 is an enlarged fragmentary plan view illustrating the improved form of terminal element with the bridge spring in place.

60 Figure 3 is an enlarged fragmentary sectional view taken approximately on the line 3-3 of Figure 2 and illustrating the manner in which the locking tongue of the bridge spring is positively deflected into active locking engagement with the slotted portion of 65 the terminal element.

65 Figure 4 is an enlarged sectional plan view taken approximately on the line indicated at 4-4 in Figure 3.

70 Figure 5 is a plan view of a bridge spring equipped with the locking tongues in its opposite terminals.

75 Referring to the drawings by characters of reference, A designates the bridge spring of a folding Oxford which is detachably associated with a terminal element B, which terminal element is in turn pivotally associated as at C with the lens rim D in the usual manner. Heretofore the terminal element B has been provided with a longitudinally extending 80 socket E having converging side walls F, which socket was designed to snugly receive the tapered terminals G of the bridge spring A, the socket being formed on its under side with a slot H designed to receive the locking 85 tongue I formed in each of the bridge spring terminals G. Obviously, the tongues I are normally bent or deflected downwardly and are intended under their inherent resiliency to snap into the slot H and engage with the 90 front wall J of the slot H. In practice, however, it has been found that frequently the tongues I fail to snap into their deflected active locking position and, obviously, it becomes necessary to remove the bridge spring 95 from the terminal element, rebend and, in some instances, re-temper the tongue I, as it is undesirable to discard the bridge spring, especially where the same is constructed of a precious or semi-precious metal. It is,

100

therefore, the aim of the present invention broadly to devise suitable means for facilitating the positive deflection of the tongue I into the slotted portion H and by way of illustration, the present invention comprehends the provision of an aperture K in the terminal element B, which aperture is disposed opposite the slot H and which aperture communicates with the socket E to permit of the introduction through said aperture K of a suitable implement L, such as illustrated in broken lines in Figure 3. It thus follows that in event of the failure of the tongue I to snap into its active locking position, the manufacturer has only to introduce any suitable implement such as illustrated, through the aperture K and to engage the same with and positively deflect the tongue I to the locking position. The aperture K is extremely small and unobtrusive and ordinarily would not mar the appearance of the frame but, if desired, a rosette or other ornamentation M may be formed by the aperture K to further mask the aperture from view.

From the foregoing, it will thus be seen that an improvement in detachable connections between a bridge spring and a terminal element has been devised which overcomes a deficiency in that form of detachable connection which has heretofore existed, and this without increasing the cost of manufacture or materially altering the usual structure.

35 What is claimed is:

1. In a socketed bridge spring terminal element having a slotted portion for receiving a locking tongue formed on the bridge spring terminal, means defining a passage-
40 way in said terminal element for admitting an instrument to positively deflect said tongue into the slotted portion of said terminal element.
2. In a socketed bridge spring terminal ele-
45 ment having a slotted portion for receiving a locking tongue formed on the bridge spring terminal, means for facilitating the positive deflection of the tongue into the slotted portion of said terminal element consisting of
50 an apertured portion of said terminal element disposed opposite the slotted portion to receive therethrough an implement for engaging and deflecting the tongue into the slot of said slotted portion.
3. In a socketed bridge spring terminal element having a slotted portion for receiving a locking tongue formed on the bridge spring terminal, means for facilitating the
55 positive deflection of the tongue into the slotted portion of said terminal element consisting of an apertured portion of the terminal element disposed opposite the slotted portion thereof and communicating with the socket
60 to receive therethrough, an implement for

engaging and deflecting the tongue into the slot of said slotted portion.

4. In a detachable connection between a bridge spring and a socketed terminal element within the socket of which element the bridge spring terminal snugly fits and in which said terminal element is provided with a slot and the bridge spring terminal with a tongue adapted to engage within said slot; an aperture formed in said terminal element directly opposite said slot, to afford means through which an implement may be projected for facilitating the positive deflection of the tongue into the slotted portion of the terminal element for effecting the active locking 80 engagement of the tongue with the slot.
